UNITED STATES PATENT OFFICE.

BENJAMIN F. WHITE, OF NEWARK, NEW JERSEY.

AUTOMATIC SOLDERING-TOOL.

941,218.

Specification of Letters Patent. Patented Nov. 23, 1909.

Application filed May 17, 1909. Serial No. 496,358.

To all whom it may concern:

Be it known that I, BENJAMIN F. WHITE, a citizen of the United States, residing at Newark, in the county of Essex and State 5 of New Jersey, have invented a new and useful Automatic Soldering-Tool, of which the following is a specification.

The objects of the invention are, generally, the provision in a merchantable form of a 10 device of the class above mentioned which shall be inexpensive to manufacture, facile in operation, and devoid of complicated parts; specifically, the provision of a burner of novel and improved construction; of a 15 soldering head adapted to be assembled with said burner; and of novel means for regulating the flow of fuel to the burner; other and further objects being made manifest hereinafter as the description of the invention progresses.

The invention consists in the novel construction and arrangement of parts herein-after described, delineated in the accompanying drawings, and particularly pointed out 25 in that portion of this instrument wherein patentable novelty is claimed for certain distinctive and peculiar features of the device, it being understood, that, within the scope of what hereinafter thus is claimed, 30 divers changes in the form, proportions, size, and minor details of the structure may be made, without departing from the spirit or sacrificing any of the advantages of the invention.

Similar numerals of reference are employed to denote corresponding parts throughout the several figures of the drawings.

In the accompanying drawings, Figure 1 40 shows my invention in longitudinal section, parts being shown in elevation; Fig. 2 is a side elevation of the wick and the wick rod which is assembled therewith, parts being shown in section; Fig. 3 is a transverse section on the line A—B of Fig. 1; and Fig. 4 is a top plan of the wick rod and of the head which is assembled therewith.

Since the device herein disclosed is adapted 50 to be used manually, it is obvious that it may be disposed in any position. In order, however, properly to define the location of the parts, the device will be presupposed to be held in an upright position, and the terms "upper," "lower," and the like, will be selected accordingly.

In carrying out my invention, I provide

primarily a reservoir 1, tubular in form, and, for convenience, made relatively long in proportion to its cross-sectional dimension. At its lower extremity, the reservoir 60 1 is constricted to form a shank 2 upon which is mounted a handle 3.

In its side wall, adjacent the handle 3, the reservoir 1 is thickened to form a shoulder 4 projecting into the interior of the device, 65 and this shoulder 4 is provided with a threaded aperture adapted to receive removably, a plug 5, which, upon its removal, leaves open the aperture in the shoulder 4, whereby the reservoir 1 may be filled with 70 any suitable liquid fuel.

The invention further includes a burner denoted generally by the numeral 6, the same comprising a tubular body portion 7 which is open at one end. One end of the 75 burner 6 is reduced to form a neck 8, which may be threaded at its lower extremity, to engage an inwardly projecting shoulder 9, located in the upper end of the reservoir 1. If desired, a lock nut 10 may be mounted 80 upon the neck 8, to hold the burner rigidly assembled with the reservoir.

The neck 8 of the reservoir is provided with an axial bore 11, a portion of the burner 6 intervening between the upper extremity 85 of the bore 11 and the lower extremity of the combustion chamber 26 of the burner. The neck 8 is provided, adjacent the point where it merges into the tubular body 7 of the burner, with a laterally disposed opening 12, which, piercing the side wall of the neck 8, communicates with the bore 11, slightly below the upper extremity thereof. A needle valve 14, is threaded to engage the opening 12, and constitutes a means whereby the fuel may be regulated in its flow 90 from the reservoir 1 to the burner 6, a combustion orifice 15, preferably tapering in form, leading from the opening 12 through the lower end of the burner 6.

The tubular body 7 of the burner, is provided with air holes 16, disposed in its side wall, relatively near to the lower end of the burner. There may be any number of these apertures 16; in the present instance, I have provided two of them, one being disposed in the position shown in Fig. 1, and the other being disposed diametrically opposite therefrom. The tubular body 7 is pierced adjacent its upper end, by circumscribing 110 rows of apertures 17, there being, in the present instance, two rows of these holes.

Mounted in the bore 11 of the neck, is a wick 18 preferably fashioned from cotton or like material. One end of this wick 18 is mounted somewhat compactly in the bore 5 11 of the neck, the other end thereof being disposed within the reservoir 1.

For the adjustment of the wick 18, a wick rod 22 is provided. One end of this wick rod is disposed in the reservoir 1, the other 10 end thereof being disposed in the bore 11 of the neck and arranged to engage the wick 18 so that, when the burner is removed from the reservoir, the end of the wick rod which is disposed in the reservoir, may be grasped, 15 whereby the position of the wick 18 in the bore 11 may be adjusted. In Fig. 2, this wick rod is shown in detail, and by a reference to said figure, it will be seen that the element consists of a straight shank 23 bent 20 at one end to form an eye 24, and, at the other end provided with a head taking the form of a flat plate 25. Adjacent one end, this plate 25 is provided with apertures 26 and 27. The shank 23 is passed along one 25 face of the plate 25, and bent, at an angle to the plane of the plate, to form a shoulder 30, and then passed through the aperture 27 along the opposite face of the plate, the terminal of the member being carried through 30 the aperture 26 and downbent upon the same side of the plate along which the shank 23 is carried in the first instance. The plate 25 is transversely depressed to form a seat 28, and the portion 29 of the wick rod is depressed to fit in the seat 28, as clearly shown 35 in Fig. 2. This seat is adapted to receive a lashing 31, which, passing about the plate 25 and the wick 18, serves to assemble the wick with the wick rod, the shoulder 30 40 serving to retain the wick in place, and to keep the lashing 31 from moving from the position shown in the drawing.

The soldering head 19 is provided with a reduced neck 20 adapted to be mounted in 45 the open end of the burner 6, a pin 21 being passed transversely through the side walls of the burner, and through the reduced portion 20 of the soldering head, to hold the parts together. This element 21 is removably mounted in the structure wherewith it 50 is assembled, so that a given soldering head may readily be removed and replaced by another of different size or shape.

In practical operation, the tool being inverted 55 the fuel which is disposed in the reservoir 1 will pass through the bore 11 of the neck 8 under the action of gravity, traversing the opening 12 and the combustion orifice 15. At the mouth of the combustion orifice 15 the fuel is lighted, the apertures 16 creating a draft to the rear of the blaze, and the apertures 17 creating a draft at the soldering head 19, tending to draw the blaze toward the soldering head.

65 The wick 18 which is mounted in the bore

11 of the neck, serves to regulate the flow of the fuel from the reservoir 1 to the combustion orifice 15, preventing the said orifice from being flooded. By sliding the wick rod 22 in the bore of the neck 8, the amount 70 of the wick 18 which is disposed in said bore may be increased or diminished at will. The amount of fuel which will flow from the reservoir to the burner will be regulated and controlled by the amount of the wick 75 18 which is disposed in the bore of the neck 8, the fuel flowing more readily when but a small portion of the wick is disposed in the neck, and with greater difficulty, when, as shown in Fig. 1, the bore 11 is substantially 80 filled by the wick.

When the flow of the fuel has been approximately adjusted by moving the wick as hereinbefore described, the flow may be adjusted to a nicety, and entirely shut off, by 85 means of the needle valve 14. It is to be observed that the wick 18 is spaced from the flame of the burner, the said wick serving merely as a means for regulating the flow of the fuel. Since the fuel is consumed 90 at the mouth of the combustion orifice 15, and not in contact with the wick 18, the said wick will need but infrequent replacement.

As shown in Fig. 1, the wick 18 may be arranged to extend completely across the 95 opening 12, and by this construction, the flow of the liquid from the reservoir to the burner may be controlled with certainty. The needle valve 14 may be advanced in the opening 12, to engage the wick 18, when the 100 latter extends across the opening 12, and by this construction, the wick may be held when the burner is removed from the reservoir.

Having thus described my invention, what I claim as new and desire to protect by Letters Patent is:

1. In a device of the class described, a burner; a reservoir assembled with the burner; a wick carried by the burner; a wick rod disposed at one end in the reservoir; a plate assembled with the other end of the wick rod, and transversely depressed to form a seat; a lashing disposed in the seat and arranged to assemble the wick with the plate.

2. A device of the class described comprising a tubular burner provided with an axial bore terminating within the burner, there being an opening in the burner intersecting the bore between its ends, and a combustion orifice leading from the opening to the combustion chamber of the burner; a wick located in the bore and arranged to be advanced to extend upon either side of the opening; means located in the opening for uncovering and closing the combustion orifice; and a reservoir assembled with the burner and communicating with the bore thereof.

3. A device of the class described com-

prising a tubular burner provided with a neck having an axial bore terminating adjacent the burner proper, the neck being provided with an opening piercing the wall 5 of the neck and intersecting the bore between its ends, there being a combustion orifice leading from the intermediate portion of the opening into the interior of the burner; a wick located in the bore and ex- 25 tended upon either side of the opening; a needle valve operable from the exterior of the device, located in the opening and arranged to uncover and to close the combustion orifice and to engage the wick; and a 10 reservoir assembled with the neck.

4. A device of the class described comprising a tubular burner provided with a neck having an axial bore terminating adjacent the burner proper, the neck being 15 provided with an opening piercing the wall

of the neck and intersecting the bore between its ends, there being a combustion orifice leading from the intermediate portion of the opening into the interior of the burner; a wick located in the bore and ex- 25 tended upon either side of the opening; means located in the opening and operable from the exterior of the device, for uncovering and closing the combustion orifice, said means being arranged to engage the 30 wick; and a reservoir assembled with the neck.

In testimony that I claim the foregoing as my own, I have hereto affixed my signature in the presence of two witnesses.
